PERFORATING DEVICE

Calvin P. Kipp, Summit, N. J., assignor to Speed Products Company, Long Island City, N. Y.

Application January 18, 1944, Serial No. 518,681

11 Claims. (Cl. 164—91)

The invention is a manually controlled punch for perforating sheets of paper and its object resides in providing a simplified punch construction having spaced brackets to slidably guide normally raised and resiliently controlled perforating or cutting tools adapted to be downwardly displaced by spaced inverted yoke shaped actuator members pivotally mounted on spaced channelled shaped members carried by the brackets, the yoke shaped members being straddled by the channel shaped members and concomitantly operated by a unitary handle for downwardly displacing the cutting tools. The invention has as another object the provision of spaced rods disposed widthwise of the yoke shaped actuator members and spaced from the fulcrum means pivotally sustaining the actuator members for depressing the resilient controlled cutting tools upon manual displacement of the handle. Other important features and structural and functional aspects of the invention will appear from the following detailed specification considered in the light of the accompanying drawings wherein:

Fig. 1 is a perspective view of the perforating device according to my invention.

Fig. 2 is a plan view of Fig. 1.

Fig. 3 is a longitudinal sectional view on the line 3—3 of Fig. 2.

Fig. 4 is a transverse sectional view on the line 4—4 of Fig. 3 and

Fig. 5 is a view similar to Fig. 4, illustrating the handle depressed for operating the cutting tools.

The cutting tools or punches T are slidably and vertically guided in aligned openings 10 and 11 of the spaced upper and lower arms 12 and 13 of sheet metal brackets B and in openings 14 of the U shaped saddles S having their lower walls 14' fixed by rivets 15 to the arms 12 of the brackets whereby wings 16 of the saddles S closely straddle the upper arms 12 and extend appreciably above the latter and characterize means for fixedly retaining fulcrum pins 17 on which the spaced and depending ears 18 of the spaced actuator members A closely straddled by wings 16 are pivotally mounted.

The tool actuator members A each fixedly carries a cylindrical tool driving pin or abutment brace 20 extending widthwise across the channel thereof and each actuator member A is provided with aligned front and rear lugs 21 and 22 integrally extending from the upper wall 23 for fixedly retaining spaced arms 24 of the handle H which is preferably formed of a relatively rugged perforated rod or heavy wire having tapered portions 25 merging into the anterior arcu-

ate portion or loop 26 fixedly retained and snapped into the annular groove 27 of the disc shaped thrust receiving head or knob 28.

As previously stated, pivoted tool actuators A 5 characterize channelled shaped members with the upwardly extending lugs 21 and 22 thereof projecting from the front and rear ends of walls 23 and normal to the spaced ears 18 depending from the sides of the inclined walls 23 common to lugs 10 21 and 22 and depending ears 18. Saddles S may also be said to be channelled shaped members.

Lower arms 13 of the brackets B are spaced from the die plates D but are secured thereto by rivets 29 passing through offset lips 30 and the 15 paper supporting base plate P. The upper arms 12 each embody an inclined rear leg 31 having an offset lip 32 fixed by rivet 33 to the die plates on platform P. However lips 30 are integrally merged to the lower arms 13 by the inclined portions 34. Brackets B may be said to be channel shaped sheet metal stanchions for slidably guiding the cutting tools T. Hence die plates D and the brackets define gaps G to permit insertion of one or more sheets of paper PP positioned first 20 under and then perforated by the punches or cutting tools T and insertion of the paper is limited by the fixed stop 34' disposed medially of the base.

The tool steel punches T each include a 30 restricted neck 35 in which is fixedly secured the annulus or flange 36 characterizing a stop to limit upward displacement of the cutting tools each of which is surrounded by a helicoidal spring 37 which serves to automatically elevate punches T from the perforations 38 in the die plates and from the latter upon removal of hand pressure on knob 28. During such operation the upper parts of the cutting tools drive the fixed rods or braces 20 causing tool actuators A to be 40 bodily rocked or tilted rearwardly about the fixed fulcrum pins 17, and hence handle H is pivoted or raised rearwardly and normally is held in such raised or tilted position, being limited in its rearward displacement when rear corners 40 of the 45 spaced depending ears 18 of the actuators A strike the upper walls 12 of the brackets.

Preparatory to punching, one or more sheets of paper PP are first inserted into gaps G until they strike the fixed projection stop 34'. Thereafter handle H is manually depressed. Consequently actuators A are rocked or pivoted forwardly. Hence the fixed rods 20 cause the tools T to be shifted downwardly and against the resistance of the springs 37 which become compressed due to the displacement of fixed ring

shaped flanges 37 carried by the tools. The tools pass through the sheets of paper and into the die plates and the severed portions 40' of the sheets of paper fall into wells 41 and onto a closure 42 rotatably mounted on screw 43 threaded into the platform or paper supporting base P. The screw is so adjusted that the upper surface of the rotatable closure 42 normally frictionally bears against surface 45 of the circular recess 46 and thus the closure may be held in a desired closed or open position and extends diametrically of the recess to close wells 41 or may be conveniently moved by finger pressure to be free of the wells to permit the latter to be emptied.

The base P and knob 28 are of a suitable wood or plastic while the remaining parts of the perforating device are of metal, although the cutting tools are of tool steel and it should be observed that on downward displacement of the wired handle, front and spaced corners 47 of actuators A cooperate with the upper horizontal arms of the brackets or stanchions B to limit such downward displacement. If desired a graduated gage bar 48 overhanging the platform has one end secured in the notch 49 thereof by a suitable set screw 50. The spaced die plates D however are initially positioned in the spaced elongated recesses 51 disposed longitudinally of the base P and characterize means for initially positioning the die plates relative to the base and are of such depth to arrange the upper faces 52 of the die plates substantially flush with the upper surface 53 of the base, the forward walls of the recesses or notches 51 being uninterrupted and curved to position and limit the displacement of the correspondingly shaped curved ends of the die plates in which instance the bolt receiving openings of the die plates line up with the bolt receiving openings of the base.

Various changes may be made in details of construction and arrangement of parts without departing from the spirit of the invention or sacrificing any of the advantages therein.

I claim:

1. In a perforating device, a base having spaced die plates provided with openings, spaced brackets mounted on said plates and having upper and lower arms including alined guide means in alignment with said openings, channeled shaped saddles secured to said upper arms and having wings straddling the latter, cutting tools slidably guided in said openings, guide means and saddles, said lower arms having portions spaced from said die plates to define therewith spaced gaps, collars carried by said tools, spring means encompassing said tools and cooperating with said collars for normally holding said collars elevated to arrange said tools out of said gaps, spaced actuator means, connecting means pivotally securing said actuator means to said saddles, abutment means carried by said actuator means and spaced from said connecting means for depressing said cutting tools towards said base, and a handle connected to said actuator means to downwardly tilt the latter for bodily displacing said abutment means to shift said tools against the resistance of said spring means and to project said tools across said gaps and into said openings.

2. In a perforating device, a base having spaced die plates provided with openings, spaced brackets mounted on said plates and having upper and lower arms including alined guide means in alignment with said openings, channeled shaped saddles secured to said upper arms and having upstanding wings straddling the latter, cutting

tools slidably guided in said openings, guide means and saddles, said lower arms having portions spaced from said die plates to define therewith spaced gaps, collars fixedly carried by said tools, spring means encompassing said tools and cooperating with said collars for normally holding said collars elevated to arrange said tools out of said gaps, spaced actuator means, connecting means pivotally securing said actuator means to said saddles, abutment means carried by said actuator means and spaced from said connecting means for depressing said cutting tools toward said base, spaced lugs extending from said actuator means, and a handle secured to said lugs to downwardly tilt the actuator means for bodily displacing said abutment means to shift said tools against the resistance of said spring means and to project said tools across said gaps and into said openings.

3. In a perforating device, a base having spaced die plates provided with openings, spaced brackets mounted on said plates and having upper and lower arms including alined guide means in alignment with said openings, channeled shaped saddles secured to said upper arms and having upstanding wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars for normally holding said collars elevated to arrange said tools out of said gaps, spaced actuator means having spaced sides, connecting means pivotally securing said sides to said saddles, brace means carried by said actuator means and spaced from said connecting means for depressing said cutting tools towards said base, and a handle connected to said actuator means to downwardly tilt the latter for bodily displacing said brace means to shift said tools against the resistance of said spring means and to project said tools across said gaps and into said openings.

4. In a perforating device, a base having spaced die plates provided with openings, spaced brackets mounted on said plates and having upper and lower arms including alined guide means in alignment with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars for normally holding said collars elevated to arrange said tools out of said gaps, spaced actuator means having spaced sides, connecting means pivotally securing said spaced sides to said saddles, abutment means fixedly interposed between said sides and spaced from said connecting means for depressing said cutting tools towards said base, a handle secured to said actuator means to downwardly tilt the latter for bodily displacing said abutment means to shift said tools against the resistance of said spring means and to project said tools across said gaps and into said openings on the downward stroke of said handle, and said collars cooperating to limit the elevation of said tools on the upward stroke of said handle.

5. In a perforating device, a base having spaced die plates provided with openings, spaced brackets mounted on said plates and having upper and

lower arms including alined guide means in alinement with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars for normally holding said collars elevated to arrange said tools out of said gaps, spaced actuator means having spaced sides, connecting means pivotally securing said sides to said saddles, abutment means fixedly interposed between said sides and spaced from said connecting means for depressing said cutting tools towards said base, and a handle connected to said actuator means to downwardly tilt the latter for bodily displacing said abutment means to shift said tools against the resistance of said spring means and to project said tools across said gaps and into said openings, and said sides having corner portions cooperating with said upper arms for limiting tiltable displacement of said saddles.

6. In a perforating device, a base having spaced die plates provided with openings, spaced brackets mounted on said plates and having upper and lower arms including alined guide means in alinement with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced actuator means having spaced sides, connecting means pivotally securing said sides to said wings, abutment means fixedly interposed between said sides and spaced from said connecting means for depressing said cutting tools towards said base, spaced lugs carried by said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon removal of said manual pressure whereby said tools rearwardly actuate said abutment means for bodily tilting said actuator means rearwardly, and means to limit tiltable displacement of said actuator means.

7. In a perforating device, a base having spaced die plates provided with openings, spaced brackets mounted on said plates and having upper and lower arms including alined guide means in alinement with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced ac-

tuator means having spaced sides, connecting means pivotally securing said sides to said wings, abutment means fixedly interposed between said sides and spaced from said connecting means for depressing said cutting tools towards said base, spaced lugs carried by said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon removal of said manual pressure whereby said tools rearwardly actuate said abutment means for bodily tilting said actuator means rearwardly, means to limit tiltable displacement of said actuator means, said handle characterizing a loop including a restricted portion, and a grooved knob snapped into and retained by said restricted portion.

8. In a perforating device, a base having spaced die plates provided with openings, spaced brackets mounted on said plates and having upper and lower arms including alined guide means in alinement with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced yokes having spaced depending sides, connecting means pivotally securing said sides to said wings, abutment means fixedly interposed between said sides and spaced from said connecting means for depressing said cutting tools towards said base, spaced lugs normal to said sides and wings and carried by said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon removal of said manual pressure whereby said tools rearwardly actuate said abutment means for bodily tilting said actuator means rearwardly, and stop means to limit tiltable displacement of said actuator means.

9. In a perforating device, a base having spaced die plates provided with openings, spaced brackets mounted on said plates and having upper and lower arms including alined guide means in alinement with said openings, channeled shaped saddles secured to said upper arms and having wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced yokes having spaced sides closely straddled by said wings, connecting means pivotally securing said sides to said wings, abutment means disposed

widthwise of said yokes and fixedly interposed between said sides and spaced from said connecting means for depressing said cutting tools towards said base, spaced lugs projecting upwardly from said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon removal of said manual pressure whereby said tools rearwardly actuate said abutment means for bodily tilting said actuator means rearwardly, and means to limit tiltable displacement of said actuator means.

10. In a perforating device, a base having spaced die plates provided with openings, spaced brackets mounted on said plates and having upper and lower arms including alined guide means in alinement with said openings, channeled shaped saddles secured to said upper arms and having upstanding wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced actuator means having spaced sides, connecting means pivotally securing said sides to said wings, abutment means fixedly interposed between said sides and spaced from said connecting means for depressing said cutting tools towards said base, spaced lugs carried by said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon re-

moval of said manual pressure whereby said tools rearwardly actuate said abutment means for bodily tilting said actuator means rearwardly, inclined means cooperating with said upper arms to limit tiltable displacement of said actuator means, said brackets being hollow and having front vertical walls integral with said upper and lower arms and inclined legs integral with said upper arms.

10. 11. In a perforating device, a base having spaced die plates provided with openings, spaced brackets mounted on said plates and having upper and lower arms including alined guide means in alinement with said opening, channel shaped yokes secured to said upper arms and having upstanding wings straddling the latter, cutting tools slidably guided in said openings, guide means and saddles, said lower arms having portions spaced from said die plates to define therewith spaced gaps, collars fixedly carried by said tools, spring means encompassing said tools and cooperating with said collars and lower arms for normally holding said collars elevated to arrange said tools out of said gaps, channel shaped and spaced actuator means having spaced sides, connecting means pivotally securing said sides to said wings, abutment means fixedly interposed between said sides and spaced from said connecting means for depressing said cutting tools towards said base, spaced lugs carried by said actuator means, a wire characterizing a handle connected to said lugs to downwardly tilt said actuator means upon application of manual pressure on said handle for bodily displacing said abutment means to shift said tools downwardly against the resistance of said spring means and to project said tools across said gaps and into said openings, said spring means bodily raising said tools out of said openings and gaps upon removal of said manual pressure whereby said tools rearwardly actuate said abutment means for bodily tilting said actuator means rearwardly, means to limit tiltable displacement of said actuator means, said base having spaced wells in alinement with said openings, and a rotatable closure normally concealed within said base for removably covering said wells.

CALVIN P. KIPP.
